UNITED STATES PATENT OFFICE

WILLARD M. COFFIELD AND THOMAS C. MOORE, OF LITTLE ROCK, ARKANSAS

CLARIFIER

Application filed December 15, 1927. Serial No. 240,186.

This invention relates to improvements in clarifiers, particularly for use with gasoline or similar cleaning fluids, and has for one of its principal objects the provision of an 5 odorless clarifying system, which will eliminate the necessity of keeping on hand large quantities of gasoline or cleaning fluid, as in this device a relatively small amount of fluid is continuously cleaned and kept in 10 place at all times.

One of the important objects of this invention is to provide, in a gasoline clarifier, means for automatically stopping the operation of the same when the gasoline becomes 15 too dirty, or if moisture rises to such an extent as to contact with the filtering elements. The device further eliminates any chance of overflow or waste of gasoline as a result of failure to clean when necessary, and will not 20 operate until surplus moisture has been eliminated.

Still another important object of this invention is to provide, in a clarifier, means for visually inspecting the contents of cleaning fluid in the washing compartment at all 25 times, and further means for continuously removing dirt from the cleaning fluid as the same is taken from the garments in the washer.

Still another and further important object 30 of this invention is to provide, in a clarifier, means for using a very cheap filtering element or moisture absorbent, enabling the same to be thrown away when dirty, with practically no loss, and further means for readily and economically effecting such a change.

Other and further important objects of 35 the invention will be apparent from the disclosures in the accompanying drawings and following specification.

The invention, in a preferred form, is illustrated in the drawings and hereinafter more fully described.

In the drawings:

Figure 1 is a side elevation of the improved clarifier of invention, parts being broken away to show interior construction.

Figure 2 is a detail view of the automatically operated moisture proof safety device.

Figure 3 is a further detail view showing the valve operated in conjunction with the safety device.

Figure 4 is a partial sectional view, taken on the line 4-4 as indicated in Figure 3. 55

Figure 5 is a detail view of the sight glass 5 for inspecting the condition of the cleaning fluid in the washer.

As shown in the drawings:

The reference numeral 10 indicates generally a pipe leading from the washer, and which is fitted with a valve 12 adjacent a button trap 14, which catches and retains buttons and similar objects which might be removed from the clothes in the process of 60 washing. After leaving the trap, the gas is passed through a pump 16 driven by a motor 18, the pump being of low speed, large volume construction, although there is provided a high speed pulley 17 for pumping over to 65 the treating tank for cleaning out purposes, and also for drawing gas from underground storage when such storage is used. In this way the expense of two pumps is eliminated. The pipe 20 is provided for intake from un- 70 derground storage, when used. 75

The pump 16 forces the fluid upwardly through the pipe 22 thence through a sight-glass 24, illustrated in more detail in Figure 5, and thence downwardly through a moisture trap, comprising a cylinder 26, which in ordinary operation allows the gasoline to pass downwardly therethrough, through a pipe 78, and thence upwardly into a clarifier tank 30. 80

In the event that a very heavy mud or dirt accumulates in the bottom of the clarifier, or if moisture rises in the clarifier through the filter element, gasoline will back up through the pipe 78 into the cylinder 26, raising the 85 float 31, which is provided with a stem 32 projecting upwardly through the top of the container 26, and this in turn will operate a trip 34, which will allow a release lever 36 to drop under the pull of a helical spring 38, 90 thereby closing the valve 40. The valve 40 is provided with an operating lever 42, which is mounted on a rotatable shaft 44, this shaft in turn passing through the body of the valve 40, as best shown in Figure 4, and having 100

mounted thereon an operating element 46, which in turn moves a pair of discs 48 into position to close ports 50, forming part of the valve structure 40.

5 Fitted in the lower portion of the clarifier tank 30 is a removable wire basket 52, having a filter spreader 54 attached thereto and depending therefrom, as best shown in Figure 1. This is made of welded steel, and can be 10 readily removed and washed when necessary.

The incoming gas from the pipe 78 strikes this cushioned spreader, which throws it in all directions without undue agitation and then passes upwardly through any desired 15 chemical material which may be placed in the clarifier for cleaning the gasoline, and thence through another spreader.

Above this the dirt from the gasoline is held, and as the fluid works upwardly it 20 passes through the moisture trap shown at 56, which is composed of a pair of wire nettings so arranged as to be readily removed and cleaned, and which is adapted to be filled with a cotton by-product similar to 25 cotton waste which will absorb in water or gasoline. The pipe 58 leads from the clarifier to the washer, and gasoline passing therethrough is completely cleaned and ready to be used in the further washing or cleaning 30 of clothes or similar articles.

Adjacent the clarifier is positioned an open top funnel 60, which is used in connection with the dirt trap, to which it is attached. Gasoline enters this trap and the air is 35 released before it passes into the continuous flow chamber 30, thence going further toward elimination of agitation. This funnel is also used as a vent pipe and as a means for recharging the clarifier with chemicals without removing or interfering with any other 40 part of the mechanism.

A valve 62 is mounted on the clarifier, leading into a pipe 64, which in turn drains into a treating tank 66, which treating tank is 45 empty at all times except when the valve 62 is opened for cleaning out the tank 30 or for treating old gasoline. A sight-glass 68 extends from the top to the bottom of this treating tank, so that the quantity and quality 50 of the gasoline therein may be readily observed.

A test valve 70 is placed on the outlet pipe of the treating tank so that a small amount of gasoline or cleaning fluid may be withdrawn for test before pumping into the tank 55 30 for the usual run.

In the bottom of the treating tank is provided a muck draining valve 72, which is used for draining mud and filth from the bottom 60 of the tank, this cleaning becoming necessary only at long intervals.

For cleaning the clarifying chamber 30 all the gasoline therein is pumped over to the storage tank 66, after which the filtering elements, wire baskets, etc., may be removed and

readily cleaned, and the interior walls of the tank washed, after which the baskets and filters and the top 74 are replaced and the device is again ready for operation.

It will be obvious that herein is provided a clarifier which at all times and in continuous operation treats all of the gasoline for a cleaning plant and without the necessity of maintaining a large volume of gasoline on hand, and this system requires only a relatively small amount of gasoline, say from 70 twenty to forty gallons, plus the gasoline in the washer, instead of the systems which have heretofore been used requiring five hundred to five thousand gallons.

75 Further, the device is safe, eliminating accidents, and is efficient and satisfactory in operation.

We are aware that many changes may be made and numerous details of construction varied throughout a wide range without departing from the principles of this invention, and we therefore do not purpose limiting the patent granted hereon otherwise than as necessitated by the prior art.

90 We claim as our invention:

1. In a clarifier, means for continuously removing foreign material from a fluid while the fluid is acting in a cleaning capacity, said means including automatically operating moisture and dirt removing traps for stopping 95 said continuous operation when an excess amount of foreign material accumulates, said trap comprising a cylinder in the system, a float in the cylinder, a valve adjacent the cylinder, and means connected with the float for automatically closing said valve when the float attains a certain predetermined height.

100 2. In a clarifier, means for continuously removing foreign material from a fluid while the fluid is acting in a cleaning capacity, said means including an automatically operating trap for stopping said continuous operation when an excess amount of foreign material accumulates, said trap comprising a cylinder in the system, a float in the cylinder, a valve adjacent the cylinder, and means connected with the float for automatically closing 105 said valve when the float attains a certain predetermined height, said means comprising a lever handle in the valve, a helical spring normally maintaining said handle in closed position, and a manually set trip operating to maintain said handle in open position, said trip being operated by the float.

110 3. An automatically operating closure valve for clarifiers, comprising a cylinder in the clarifying pipe line, a float in the cylinder, a valve in the pipe line adjacent the cylinder, and means operated by the float to close said valve when the float attains a certain predetermined height, said means comprising a pin on the float extending upwardly 115 through the top of the cylinder, a resilient 120 125

element connected to the valve and normally acting to close the same, and a trip means adapted to be manually set to maintain the valve in open position, said trip means being sprung by the float rod.

In testimony whereof we affix our signatures.

WILLARD M. COFFIELD.
